United States Patent Office.

GEORGE WOODS, OF CAMBRIDGE, MASSACHUSETTS.

Design No. 4,546, dated December 27, 1870.

DESIGN FOR THE CASE OF A PARLOR-ORGAN.

The Schedule referred to in these Letters Patent and making part of the same.

To all whom it may concern:

Be it known that I, GEORGE WOODS, of Cambridge, in the county of Middlesex and State of Massachusetts, have invented an improved Design for Parlor-Organs; and I do hereby declare that the following, taken in connection with the drawings which accompany and form part of this specification, is a description of my invention sufficient to enable those skilled in the art to practice it.

My design relates particularly to the ornamental finish of the fronts of that class of reed-musical instruments known as parlor and cabinet-organs.

These fronts are generally made with vertical pillars and panels, more or less configurated or ornamented, and my improvement or design consists in adding to the flat faces of the panels or pillars medallions or tablets, having in relief or embossed upon them heads or busts.

To these instruments I apply the name "medallion" or "medallion-style."

The addition of the medallion imparts a fine finish to an organ, as will be seen by the accompanying

photographic representation of one of the instruments.

a denotes the front wall; and

b, one of the end walls of the case.

c c are vertical pillars at the front, these pillars having bracket-projections, *d d*, in line with the keyboard.

e e represent two medallions, shown as applied to the front faces of the brackets.

They may also be added to the surfaces *ff* below, and to the panels *g g*, if desirable, the medallions serving as the distinguishing ornament of the front, whether applied to all these surfaces or to any two or more opposite surfaces.

I claim—

The medallion design for the front of a parlor or cabinet-organ, substantially as shown and described.

GEORGE WOODS.
